UNITED STATES PATENT OFFICE.

WILHELM SCHEFCZIK, OF HAMBORN-ON-THE-RHINE, GERMANY.

MECHANICAL ROASTING-FURNACE.

1,210,852.

Specification of Letters Patent.

Patented Jan. 2, 1917.

Application filed May 22, 1914. Serial No. 840,240.

To all whom it may concern:

Be it known that I, WILHELM SCHEFCZIK, a subject of the German Emperor, residing at the city of Hamborn-on-the-Rhine, in the 5 Kingdom of Prussia, Germany, have invented certain new and useful Improvements in Mechanical Roasting-Furnaces, of which the following is a specification.

This invention relates to mechanical 10 roasting furnaces comprising stationary muffles having curved bottoms, and the primary object is to provide improved means for conveying the material along the inside of the muffles.

Another object is to provide an improved 15 conveyer for charging the muffles.

A further object is to provide improved means for driving the conveyer means in the muffles.

Another object is to provide an improved 20 bunker for supplying material to the conveyer.

Other objects of the invention are described hereinafter.

To these ends, the invention consists in the construction, arrangement and combination of parts described hereinafter and pointed out in the claims.

One illustrative embodiment of the 30 invention is diagrammatically represented by way of example in the accompanying drawings, wherein:—

Figure 1 is a longitudinal section of one form of my mechanical roasting furnace, 35 taken on the line A—B—C—D of Fig. 2. Fig. 2 is a vertical transverse section of the same. Fig. 3 is a detail view of conveyer teeth. Fig. 4 is a vertical elevation showing an improved bunker for charging the furnace, and Fig. 5 is a diagrammatic end elevation of means for driving the conveyers in the muffles.

Referring to the drawings, in the form 45 shown in Figs. 1 and 2 three muffles *a* each having approximately the form of half a cylinder are arranged with the round side downward one above another, and a second system comprising three similar muffles is arranged laterally thereof, so that in this case the furnace comprises six muffles. If preferred, each muffle may be formed as a complete cylinder. Below each tier of three muffles *a* I have provided a furnace 10 from which lead pairs of serpentine heating flues 50 having a section 11 extending from the furnace under the bottom of the lower muffle

a, thence by short vertical connecting flues 12, Fig. 1, at the rear to the next horizontal flue section 13, which connects, by a vertical flue 14 at the front, to the upper flue 60 section 15 that terminates in a vertical flue 16 leading to the stack.

Arranged within the masonry of the furnace at each side thereof are separate similar serpentine air admission flues 17, Fig. 2, each having a branch 18 to admit heated air above the grate of the furnace and a branch 19 to admit heated air below said grate. These flues may be controlled by dampers, as is customary (not shown) or these dampers may be omitted. Between the two tiers of muffles *a* arranged in a vertical plane, is a third serpentine air passage 20 having lateral extensions 21, that admits heated air into the front end of the upper muffles *a*; 22 75 that admits air to the furnace flue section 15; 23 that admits air to the rear of the second or middle muffles of the tiers; 24 that admits air to the rear end of the flue section 13, and 25 that admits air to the front 80 end of the lower muffle. This air also becomes heated in passing through the masonry to its several points of discharge.

The gases from the muffles arising from the roasting operation, and especially where 85 sulfur is evolved from the ore treated, pass from the lower muffle *a* at its rear end, up to the next muffle, through the chute 26 to the middle muffle, through the latter to its front end, thence through the chute 27 at 90 the front of the upper muffle, and are discharged through openings 28, Fig. 2, in the upper part of the rear end of said muffle to a separate stack 29, or pipe, for conveyance to a sulfuric acid plant.

All the muffles are fixedly mounted, that is to say, formed in or built in as a part of the masonry, and are not, as is usually the case, separate, removable fire-clay elements.

Each muffle has a horizontally journaled 100 hollow shaft *b*, on each of which are two or more vertical arms *c* which carry a rabbling member, *c. g.* a channel-iron or bar, located parallel with the shaft, on which bar or channel are provided exchangeable 105 teeth *d* for mixing and conveying the material to be roasted. When the muffles have only a round bottom, thus for example when the muffles are semicylindrical, there are two or more rows of teeth, the teeth of one row 110 off-set from those of the adjacent row. These teeth are isosceles triangles in plan

view with the points *d*' directed toward the front (Fig. 3) or toward the direction in which the material is to move. When two rows of teeth are provided the individual 5 triangular prisms are arranged displaced relatively to one another, in order that the material to be roasted which is pushed by the sides of the triangles toward the point and passes this point laterally arrives on to 10 the inclined plane which is formed by a side of the adjacent triangle and is thus pushed onward in the same direction, even when the teeth have imparted to them a reciprocatory motion. Fast on one end of each 15 low shaft outside the muffles is a gear-wheel *e* driven by a vertically reciprocated toothed rack *f* or the like, so that the shafts and all the stirrers have imparted to them an oscillatory motion, their teeth *d* being driven 20 to and fro over the curved bottoms of the muffles, so that the material to be roasted is fed forward while it is moved laterally on the curved bottoms of the muffles but mainly forward by the slanting faces of the teeth. 25 There must be at least two rows of these teeth *d* displaced relatively to one another, otherwise the material to be roasted would remain stationary in the space between the apex of one triangle and the base of the triangle in front. It will therefore be readily 30 understood that another arrangement is possible.

On the one end of the furnace away from the charging inlet of the top muffle is provided an ore bunker, from which the undried crude ore falls into a scraping belt or 35 push conveyer *g* (Fig. 1), conveyer worm or the like; the latter conveys the ore slowly along the top of the furnace toward the inlet at the other end of the same, whereby it 40 is gradually dried by contact with the hot roof of the furnace.

An iron hopper 30 (Fig. 1) is provided on the top at the one end of the top muffle, into 45 which projects a solid rotating cone *h* having teeth milled therein, its periphery being somewhat steeper than that of the iron hopper. The cone can be raised and lowered by the spindle *i*. The spindle *i* is rotated by a 50 suitable gear train and is adjustable. For this purpose it is slidable through a bevel pinion 31 that gears with a bevel wheel 32 on a horizontal shaft 33 carrying a pinion 34 that is actuated by a sector 35 secured on 55 the upper hollow muffle shaft *b*, there being one such feeding device for each tier of muffles. It will thus be seen that the cone *h* acts to break up the lumps, and that the feed will be proportionate to and dependent 60 upon the speed of movement of the shaft *b*; in other words, proportionate to the rate of movement of the ore through the muffle. When the cone is in its lowest position it 65 contacts with the bottom of the hopper in consequence of the difference in slant of the

sides of the two. The cone is lifted depending on the quantity of ore to be charged until the opening is sufficiently wide, but is nevertheless only so wide that the lower part of the hopper remains filled with ore 70 so that no gas can escape from the furnace. In the furnace itself the ore travels forward longitudinally in the upper muffle from the inlet to the chute 27, drops therethrough into the middle muffle, sliding down slantwise through the hopper or chute without producing dust into the next lower muffle, 75 and so on and is discharged from the lower muffle through passage 36.

The furnace gases under the muffles are 80 conducted opposite to the direction of motion of the ore in order, in combination with the heat of combustion of the material to be roasted and with a supply of preheated regulatable quantities of air for each muffle 85 through branch passages 21, 23 and 25, to accelerate the roasting process. The furnace which is heated by gas or coal can be regulated by supplying preheated regulatable quantities of air above and below the 90 grate by air flue 17 and its branches 18 and 19, and in addition preheated air can be supplied in regulatable quantities to each heating flue by flues 22, 23 and 24, so that the total combustion can be increased and 95 damped, and also the distribution of heat in the furnace itself and the drawing of the flame almost up to the flue can be regulated. If gas firing is to be used, when the furnace 100 comprises muffles arranged one over another with intermediate heating flues one or more burners 37 is or are introduced into each heating flue or flues.

The ore bunker (Fig. 4) likewise has an improved construction. Its angle of slant 105 may be adjusted and also its spout corresponding to the ease with which the different ores slide down, so that the quantity of ore supplied can be regulated, and such materials as slide only with difficulty owing 110 to being wet for example can be charged into the furnace. Owing to the bunker *k* itself and its lip or spout *l* being adjustable independently one of the other it is possible exactly to adjust the supply of the material. This is aided by the provision of a roller *m* or the like which rotates between the bunker *k* and the spout *l*, its object being to keep the material sliding uniformly 115 and to crush lumps, *e. g.* in wet ores. 120

A gate *n* arranged to move up and down in front of the roller affords another possibility of regulating the supply of the material and preventing too much falling on the roller and obstructing the latter. The gate *n* 125 is raised and lowered by a screw 40 and hand wheel 41 supported in a standard 42 on the chute *k*, the gate sliding in vertical guides 43 on the sides of the chute or bunker. The lateral guides of this gate are not continued 130

to the bottom of the bunker in order to prevent the guides being stopped up. Fig. 4 shows a side elevation of the bunker; *o* is a floor-frame for carrying the shaft *p* on which the bunker *k* proper and the spout *l* are rotatably mounted. Both are suspended from rods *r*, *s*, which can be shortened by nuts or turn buckles *s* and *t* having right and left-handed threads; in this manner it is possible to adjust the slant of the bunker *k* and its spout or lip *l* exactly and to change from one inclination to another.

10 A roller *m* is mounted at the outlet of the bunker; this roller feeds the material on the one hand, and, on the other hand, when it is necessary, disintegrates it by means of teeth or the like thereon.

15 The above-described furnace could be driven by means of a motor and transmission gearing; the same is, however, driven much more advantageously with the hydraulic means described hereinafter with reference to Fig. 5. The stirring mechanisms of all mechanical furnaces require to be driven slowly. They therefore require a large ratio of transmission by means of belting or the like in consequence of the high speed of the electric motors. This kind 20 of drive frequently requires considerable space and entails great loss of energy owing to friction. The most important defect of the said drive, however, is that it is possible to regulate the speed of the stirring mechanism only very imperfectly by means of stepped pulleys and series resistances for the motor. Particularly when roasting zinc-blendes materials have to be dealt with which on the one hand require thorough roasting 25 and on the other hand are of such various natures that only an apparatus capable of regulation within wider limits than those known heretofore can yield economical results with all kinds of ores. Reference may 30 be made merely to the differences in zinc-blendes in size of grain, hardness, percentage of sulphur and zinc, admixtures of troublesome gangues and metals, and in changing influences exercised by the many 35 processes of enrichment and treatment. These greatly changing conditions can be met only by a furnace whose stirring mechanism can have its speed regulated within wide limits and thereby causes the material 40 to be roasted to remain in the furnace for a time adapted to the kind of ore in question. These conditions are met by the apparatus 45 described hereinafter.

50 As shown in Fig. 5, gear-wheels *e* are keyed on the ends of the shafts *b* which are located horizontally in the longitudinal muffles *a*, and which carry arms *c*, having conveyer teeth *d* for the material to be roasted. These gear-wheels are oscillated 55 by a frame comprising a toothed rack *f* on

both sides, so that the stirrers have a pendulous motion imparted to them. Attached to the bottom end of the frame is a piston rod *u* which is directly connected with the piston *v* in the pump cylinder *w*. Owing to water or some other fluid being alternately supplied above and below the piston the latter is driven down and up and drives the driving mechanism and with it the stirrers in the described manner. In order to automatically reverse the direction of flow of the water under pressure at the desired moment the following reversing device is provided.

60 Attached to the piston-rod *u* is a connecting rod *x* which rotates a cone or plug valve *z* in a suitable casing or box by means of the crank *y*. This cone *z* has two recesses 1 and 2 of semicircular section in opposite sides thereof. Assuming that water under pressure flows into the recess 1 through the pipe 3, it can flow without obstruction into the pipe 4 and arrive above the piston *v* which it will drive downward. The water on the opposite side of the piston can flow through the pipe 5 into the recess 2 and can 65 escape through the pipe 6. In consequence of the connection of the cone *z* by means of the connecting rod and the crank with the piston *v*, when the latter moves the cone *z* is also rotated until the recess 1 is connected 70 with the pipes 7 and 8 and the recess 2 is connected with the delivery pipes 9 and 6; the piston and stirrers are thereby driven in the opposite direction while the pipes 3, 4, 5 and 6 are closed by the cone. 75

80 For passing over the dead point the reversing device is connected in such manner with the frame and stirrers that at the moment of reversal the frame and stirrers continue to fall a short distance and rotate 85 the cone a little farther. In order that the water under the piston shall not prevent this fall the supply and delivery pipes are displaced at the casing or box relatively to one another an amount equal to their diameter so that the rotating cone first releases the delivery pipes and then the supply pipes of the opposite side, so that the outflow of the water begins first and the water under 90 pressure flows in a moment later to the other side of the piston. By properly adjusting the cock or valve 45 in the discharge pipe provision is made that the water which has done its work does not escape too rapidly and, as it were, constitutes a cushion in 95 order to assure uniform motion of the pump piston. The valve 44 in the inlet pipe controls the water admitted. The advantages 100 of the herein-described invention may be summarized as follows:—The hydraulic driving device and the frame and stirring mechanism occupy very little space outside the muffles; in consequence of their arrangement on the narrow side or end of the furnace the attendance of the furnace and re- 105

pairs thereto are in no way obstructed. The speed of the stirrers can be regulated within very wide limits by one single manipulation by simply regulating the water supply by one cock. It can be adapted in a manner unattained heretofore to the various materials and conditions of working. The piston and stirrers can be stopped in any position and within the fraction of a second by closing cocks, which may frequently preserve the entire gearing from fracture when disturbances occur. In consequence of the simplicity unknown heretofore injury of the driving mechanism is almost impossible as all cams, balancers, springs and the like, such as are comprised in water-column machines, are avoided.

I claim:—

1. In a muffle furnace, the combination with a round bottom muffle; of a hollow shaft mounted longitudinally therein, a single rabbling member parallel with said shaft, a single series of arms connecting said member and shaft, a plurality of rows of triangular teeth rigidly secured to said member, the teeth of one row off-set from the teeth of its adjacent row, and means to oscillate said shaft.
2. In a muffle furnace, the combination with a series of superposed muffle chambers discharging by gravity through openings in their bottoms into one another; of an oscillating rabbling mechanism in each muffle comprising a shaft passing longitudinally through the muffle, and a toothed rabbling member supported by the shaft, a feeding device for the upper muffle comprising a hopper and a coöperating cone and means to rotate said cone from the shaft of a muffle.
3. In a muffle furnace, the combination with a muffle thereof; of a shaft extending longitudinally through the muffle, a rabbling member secured to said shaft and having thereon a plurality of rows of triangular teeth, a hopper discharging into the muffle, a cone coöperating with said hopper, a gear train between said shaft and cone and means for oscillating said shaft.
4. In a muffle furnace, the combination with superposed, non-removable muffles, fire flues arranged only under the soles of said muffles, means to introduce air to said flues when desired, and means to separately heat said flues when desired, and a furnace for successively heating all the fire flues of a superposed series of muffles.
5. In a muffle furnace, a shaft in each

muffle, a rabble on said shaft, a pinion on the shaft outside the muffle, a rack engaging the pinion, a hydraulic piston and cylinder, means connected with said racks for automatically reversing the flow of water to and from said piston, and means to regulate the flow of water to and from said cylinder whereby the speed of said piston and rabble may be instantly changed at will.

6. In a mechanical roasting furnace, the combination of a plurality of stationary muffles arranged one over another in groups, oscillatory mixing and conveying means comprising a horizontal shaft in each muffle, a gear wheel fast on the end of each shaft outside the muffles, a frame comprising toothed racks meshing with said gear wheels, and hydraulic means for reciprocating said frame.

7. In a mechanical roasting furnace, the combination of a plurality of stationary muffles arranged one over another in groups, oscillatory mixing and conveying means comprising a horizontal shaft in each muffle, a gear wheel fast on the end of each shaft outside the muffles, a frame comprising toothed racks meshing with said gear wheels and hydraulic means comprising a pump having a piston-rod connected to said frame, supply and delivery pipes connected to the two ends of the pump, and reversing means comprising a box connected in said pipes and a plug having recesses movable in said box.

8. In a mechanical roasting furnace, the combination of a plurality of stationary muffles arranged one over another in groups, oscillatory mixing and conveying means comprising a horizontal shaft in each muffle, a gear wheel fast on the end of each shaft outside the muffles, and a frame comprising toothed racks meshing with said gear wheels, and hydraulic means for reciprocating said frame; said hydraulic means comprising a pump having a piston rod connected with said frame, supply and delivery pipes connected to the two ends of the pump, and reversing means comprising a box connected in said pipes, a plug having recesses rotatable in said box, and means for rotating said plug connected to said piston rod.

In testimony whereof I affix my signature in presence of two witnesses.
